UNITED STATES PATENT OFFICE

100,709

DESIGN FOR A FLYING BOAT BOMBING AIRPLANE

Charles N. Monteith and Elliott G. Emery, Jr.,
Seattle, Wash., assignors to Boeing Aircraft
Company, Seattle, Wash., a corporation of
Washington

Application December 13, 1935, Serial No. 60,054

Term of patent 7 years

To all whom it may concern:

Be it known that we, Charles N. Monteith and Elliott G. Emery, Jr., both citizens of the United States, and both residing at Seattle, in the county of King and State of Washington, have invented a new, original, and ornamental Design for a Flying Boat Bombing Airplane, of which the following is a specification, reference being had to the accompanying drawing, forming part thereof.

Figure 1 is a plan view of the airplane, showing our new design.

Figure 2 is a front elevation, showing wing tip floats in their raised or retracted position.

Figure 3 is a side elevation of the airplane.

Figure 4 is an underside perspective view of the airplane in flight, on a somewhat enlarged scale from the preceding views.

We claim:

The ornamental design for a flying boat bombing airplane, as shown.

Signed at Seattle, King County, Washington,
this 7th day of December, 1935.

CHARLES N. MONTEITH.
